DESIGN FOR A GAME BOARD

Paul A. Brown, Port Orchard, Wash.

Application December 1, 1939, Serial No. 88,600

Term of patent 3½ years

To all whom it may concern:

Be it known that I, Paul A. Brown, a citizen of the United States, residing at Port Orchard, in the county of Kitsap and State of Washington, have invented a new, original, and ornamental Design for a Game Board, of which the following is a specification, reference being made to the accompanying drawing, forming a part thereof.

The figure is a plan view of a game board showing my new design.

The game board is of no substantial thickness and the design thereon is all flush with the surface.

I claim:

The ornamental design for a game board, as shown and described.

PAUL A. BROWN
